United States Patent Office.

WILLIAM M. SMITH, OF WEST MERIDEN, CONNECTICUT, ASSIGNOR TO HIMSELF AND THE MERIDEN BRITANNIA COMPANY, OF THE SAME PLACE.

Letters Patent No. 70,759, dated November 12, 1867.

IMPROVED CASKET-HANDLE.

The Schedule referred to in these Letters Patent and making part of the same.

TO ALL WHOM IT MAY CONCERN:

Be it known that I, WILLIAM M. SMITH, of West Meriden, county of New Haven, and State of Connecticut, have invented certain new and useful Improvements in Attachments for Casket-Handles; and to enable others skilled in the art to make and use the same, I will proceed to describe, referring to the drawings, in which the same letters indicate like parts in each of the figures.

The nature of this improvement consists in forming depressions in the back side of the lifting-plate, directly back of the lower screw-holes, (provided for fastening said plates with the handle to the body of a casket,) to receive the tag of the attachment, representing, by "cord and tassel," emblems, characters, or designs, signifying orders, brotherhood society, or body of persons associated together for mutual benefit.

The object designed to be accomplished thereby is, to save the trouble and expense of making an entire set of patterns or moulds, having the desired insignia made thereon; and, more important still, to save the great amount of stock and labor arising from breakage in the process of finishing, transporting, and handling.

In the accompanying drawings, A is a casket-handle. B are the lifting-plates in which the handles are secured. C are screw-holes formed in the upper and lower edges of said plates, through which screws pass into the body of the casket to hold the plates with the handle thereto. D are cord and tassel-attachments, representing various other emblems, insignia, or ornamental design. These insignia "attachments" are provided with tags E, the shape of which is designed to correspond with the shape of the lower edge of the plates B and the depressions formed in the back side of the plates B directly back of the lower screw-holes C'.

Now, it will be clearly seen that when the handle A, with the plate B, is secured to the body of a casket by screws passing through the holes C in the plate B, if at any time it is desirable to attach any insignia thereto, it can be easily done by simply removing the lower screws at C' and inserting the tag E of said "insignia attachment" into the depression formed in the back side of the plates B, near the lower edge, and directly back of the holes C', then replacing the screw through the plate B and tag E into the body of the casket, when they will become securely attached to the plates by the joint action of the screws, and the formation of the tag and depressions for receiving the same. Thus a great variety of styles can be quickly and easily produced. The handles can be used either with or without the attachments, without any disfigurement thereof or in any way affecting their symmetrical appearance.

I believe I have thus shown the nature, construction, and advantage of this improvement, so as to enable others skilled to make and use the same therefrom.

What I claim, therefore, and desire to secure by Letters Patent, is—

The employment of attachments D, or their equivalents, having tags E, in combination with the depressions formed in the plates B, substantially as and for the purpose described.

WM. M. SMITH. [L. S.]
